CLAIM

The ornamental design for an oral care applicator, as shown and described.

DESCRIPTION

FIG. 1 is a perspective view of an oral care applicator, embodying the new design;

FIG. 2 is a rear side view of the oral care applicator of FIG. 1;

FIG. 3 is a top planar view of the oral care applicator of FIG. 1; and,

FIG. 4 is a bottom planar view of the oral care applicator of FIG. 1.
